His Attorney.

UNITED STATES PATENT OFFICE.

CHARLES E. GALBREATH, OF CHANUTE, KANSAS.

PORTIÈRE ROD.

1,425,247.

Specification of Letters Patent.

Patented Aug. 8, 1922.

Application filed January 24, 1921. Serial No. 439,452.

To all whom it may concern:

Be it known that I, CHARLES E. GALBREATH, a citizen of the United States, residing at Chanute, in the county of Neosho 5 and State of Kansas, have invented a certain new and useful Improvement in Portière Rods, of which the following is a specification.

My invention relates to improvements in 10 portière rods adapted for use in connection with a door or window frame.

One of the objects of my invention is to provide a portière rod which is simple in construction, cheap to make, not liable to get 15 out of order, which eliminates the use of nails, screws or the usual pole sockets, which will not scratch or mar the door or window casing, which adapts itself for doors or windows of different widths, which can be 20 quickly and easily put up or taken down, and will reliably hold itself in operative position.

A further object of my invention is to provide a novel portière rod having two members 25 slidable neatly fitted one in the other in a manner such that when the inner rod moves outwardly, a partial vacuum is formed in the tubular member, thus preventing the members slipping accidentally 30 apart when they are being handled.

The novel features of my invention are hereinafter fully described and claimed.

In the accompanying drawing, which 35 illustrates the preferred embodiment of my invention,

Fig. 1 is an elevation of a portion of a frame having my improved portière rod mounted thereon.

Fig. 2 is an enlarged horizontal section 40 on the line 2—2 of Fig. 1.

Fig. 3 is an enlarged cross section on the line 3—3 of Fig. 1.

Similar reference characters designate 45 similar parts in the different views.

1 designates an outer tubular horizontal member having neatly slidably fitted therein a horizontal member 2, which may also be 50 tubular.

3 designates two caps respectively mounted, preferably by threaded connection, on the outer ends of the members 1 and 2. The caps 3 respectively close and support the outer ends of the members 1 and 2, so that when the member 2 moves outwardly in the 55 member 1, a partial vacuum is formed

within said members, thus preventing them from slipping accidentally apart when they are being handled.

A small bleed hole 4 may be provided in one of said members, as in the member 1, for 60 the purpose of slowly admitting air so as to permit the rod being extended or contracted.

Mounted in the member 1 is a coil spring 5 which bears at one end against the adjacent cap 3 and at its other end against the inner end of the member 2. The tension of the spring 5 normally forces the member 2 outwardly so as to cause the caps 3 to be forced tightly against the jambs 6 of a door 70 or window frame.

For the protection of the jambs 6 against scratching or abrasion by the caps 3 and to enable the latter to reliably hold their proper position against the casing, the outer side 75 of each cap 3 may have attached to it by cementing or gluing, a yielding pad 7 of felt, soft rubber, or other suitable material.

In the operation of my invention, the member 2 is forced inwardly to a position 80 in which the rod may be extended between the jambs 6, after which the spring 5 is permitted to force the member 2 outwardly, so that the pads 7 will bear tightly against the jambs 6. It will be understood that the 85 drapery to be supported may be mounted in the usual way on portière rod. If the rod is to be threaded through the drapery the members 1 and 2 are drawn apart so that this may be effected, after which the 90 member 2 is inserted, as described, in the member 1.

As the rod is retained against the jambs solely by frictional pressure, the rod may be 95 adjusted vertically or horizontally with ease to any desired position, from which position it can be as readily changed to another position without having to remove or insert any nails, screws or similar securing devices. Furthermore, the frictional supporting 100 means prevents the marring or scratching of the casing.

I do not limit my invention to the structure shown and described, as many modifications, within the scope of the appended 105 claims, may be made without departing from the spirit of my invention.

What I claim is:—

A portière rod comprising two members 110 neatly slidably fitted into and out of engage-

ment with each other, two caps respectively closing the outer ends of said members and arranged to support said members and having means for respectively engaging and being supported by two jambs of a door or window, the tubular member having a relatively small bleed hole communicating with the interior thereof and the atmosphere, and

a coil spring mounted in the tubular member and bearing at one end against the adjacent cap and bearing at its other end against the inner end of the other member, substantially as set forth. 10

In testimony whereof I have signed my name to this specification.

CHARLES E. GALBREATH.
